FIG. 5

FIG. 6

1
MIXER

PRIORITY CLAIM

This application claims priority from European Patent Application No. 17159008.6 filed on Mar. 2, 2017, the disclosure of which is incorporated by reference.

TECHNICAL FIELD

The present invention relates to a mixer. In particular the mixer is part of a gas turbine and is used to supply dilution air into the hot gas passing through the gas turbine.

BACKGROUND

FIG. 1 schematically shows an example of a gas turbine; the gas turbine **1** has a compressor **2**, a first combustion chamber **3**, a second combustion chamber **4** and a turbine **5**. Possibly between the first combustion chamber **3** and the second combustion chamber **4** a high pressure turbine is provided. During operation air is compressed at the compressor **2** and is used to combust a fuel in the first combustion chamber **3**; the hot gas (possibly partly expanded in the high pressure turbine) is then sent into the second combustion chamber **4** where further fuel is injected and combusted; the hot gas generated at the second combustion chamber **4** is then expanded in the turbine **5**.

Between the first combustion chamber **3** and the second combustion chamber **4** a mixer **7** can be provided in order to dilute with air (or other gas) the hot gas coming from the first combustion chamber **3** and directed into the second combustion chamber **4**.

FIG. 2 schematically shows the section of the gas turbine including the first and the second combustion chambers **3, 4**. FIG. 2 shows a first burner **3a** of the first combustion chamber **3** where the compressed air coming from the compressor **2** is mixed with the fuel and a combustor **3b** where the mixture is combusted generating hot gas (reference **20a** indicates the flame). The hot gas is directed via a transition piece **3c** into the mixer **7**, where air is supplied into the hot gas to dilute it. The diluted (and cooled) hot gas is thus supplied into the burner **4a** of the second combustion chamber **4** where further fuel is injected into the hot gas via a lance **8** and mixed to it. This mixture combusts in the combustor **4b** by auto combustion (reference **20b** indicates the flame), after a “delay time” from the injection into the second burner **4a**.

The temperature in the second burner **4a** can oscillate, typically because of mass flow oscillations of the air coming from the mixer **7** and directed into the second burner **4a**.

The delay time depends on, inter alia, the temperature within the second burner **4a**, such that temperature oscillations in the second burner **4a** cause increase/decrease of the delay time and thus axial upwards/downwards oscillations of the flame in the combustor **4b**.

In order to prevent these axial oscillations of the flame, the temperature in the second burner **4a** has to be maintained constant and thus the flow emerging from the mixer **7** has to be maintained constant.

The mass flow through the mixer **7** can vary because within the mixer **7** pressure oscillations exist (e.g. due to the combustion in the combustor **3b** and/or **4b**); these pressure oscillations cause an increase/decrease of the flow of diluting air injected into the mixer.

In order to maintain this flow constant, multiple injectors can be provided at different axial locations of the mixer **7**,

2

in such a way that oscillating pressure air supplied through upstream injectors compensate for oscillating pressure air supplied through downstream injectors. In other words, air is injected in such a way that high pressure air injected from upstream injectors reaches the downstream injectors when low pressure air is injected through them (and vice versa); this way the high pressure and low pressure compensate for one another and are cancelled, such that the pressure within the mixer **7** stays substantially constant; air injection into the mixer can thus be constant over time.

The inventors have found a way to improve cancellation of pressure oscillations (and thus mass flow oscillations) through the cross section of the mixer.

15

SUMMARY

An aspect of the invention includes providing a mixer with improved flow oscillation cancellation.

20 These and further aspects are attained by providing a mixer in accordance with the accompanying claims.

BRIEF DESCRIPTION OF THE DRAWINGS

25 Further characteristics and advantages will be more apparent from the description of a preferred but non-exclusive embodiment of the mixer, illustrated by way of non-limiting example in the accompanying drawings, in which:

FIG. 1 schematically shows a gas turbine;

30 FIG. 2 schematically shows the first combustion chamber, mixer and second combustion chamber of the gas turbine of FIG. 1;

FIG. 3 shows a longitudinal section of a mixer;

FIG. 4 shows a different embodiment of the gas turbine;

35 FIGS. 5 and 6 show the distance between the first, second, third, fourth injectors, in relation with the pressure within the mixer itself; in those figures the reference **0** identifies the nominal pressure within the mixer;

FIG. 7 shows an example of injectors comprising more 40 rows of nozzles, and

FIG. 8 shows a different embodiment of the mixer.

DETAILED DESCRIPTION OF EXEMPLARY EMBODIMENTS

45 With reference to the figures, these show the gas turbine **1** with the compressor **2**, the first combustion chamber **3**, the second combustion chamber **4** fed with a fluid coming from the first combustion chamber **3**, the turbine **5**. Between the first combustion chamber **3** and the second combustion chamber **4** it is provided the mixer **7**. In addition, between the first combustion chamber **3** and the second combustion chamber **4** (upstream or downstream of the mixer **7**), a high pressure turbine can be provided (FIG. 4, turbine **9**).

50 The mixer **7** comprises a housing **10**, a duct **11** within the housing **10**, a first injector **12** arranged to inject a fluid at the centre zone of the duct **11**, a second injector **13** arranged to inject a fluid at the centre zone of the duct **11**, a third injector **14** arranged to inject a fluid at the wall zone of the duct **11** 55 and a fourth injector **15** arranged for injecting a fluid at the wall zone of the duct **11**. Additional injectors can also be provided.

60 Each injector can comprise a row of nozzles **16** extending over the circumference or perimeter of the duct **11**; in addition each injector can comprise a plurality of rows of nozzles close to one another. Additionally, nozzles **16** of different rows of nozzles of a same injector can have same

or different penetration and/or nozzles **16** of a same row of nozzles can have different penetration.

For example, FIG. 3 shows an embodiment with injectors arranged for injecting the fluid at the centre zone and at the wall zone of the duct **11** that are provided close to one another.

In order to inject the fluid at the centre zone **18** of the duct **11** the first and second nozzles **12, 13** have a deep penetration into the duct **11**; likewise in order to inject the fluid at the wall zone **17** of the duct **11** the third and fourth nozzles have a small penetration into the duct **11**; generally the first and second injectors **12, 13** have a deeper penetration into the duct **11** than the third and fourth injectors **14, 15**.

The relative position of the injectors can be any, i.e. any injector can be upstream and/or downstream of any other injector (upstream and downstream are referred to the fluid circulation direction identified by the arrow **F** in the figures).

The distance between the first injector **12** and the second injector **13** is, in case there is no acoustic node between them (i.e. in the absence of an acoustic node)

$$D1 = \lambda_{conv}/2 = v/2f_1$$

or an odd integer multiple of it. In case there is an acoustic node between the first and second injectors **12, 13** (i.e. in the presence of an acoustic node) the distance **D1** is

$$D1 = \lambda_{conv} = v/f_1$$

or a full wave length integer multiple of it.

Likewise, the distance between the third injector **14** and the fourth injector **15** is, in case there is no acoustic node between them (i.e. in the absence of an acoustic node)

$$D2 = \lambda_{conv}/2 = v/2f_2$$

or an odd integer multiple of it. In case there is an acoustic node between the third injector **14** and the fourth injector **15** (i.e. in the presence of an acoustic node) the distance **D2** is

$$D2 = \lambda_{conv} = v/f_2$$

or a full wave length integer multiple of it.

In the above formulas:

f_1 is the oscillating frequency (pressure oscillation) to be damped at the wall zone **17** of the duct **11**, i.e. at zones within the duct **11** that are close to the wall, e.g. at the outer part of the flame,

f_2 is the oscillating frequency (pressure oscillations) to be damped at a centre zone **18** of the duct **11**, e.g. at the inner or centre part of the flame,

λ_{conv} is the convective wave length, i.e. the flow velocity v through the duct divided by the frequency that should be addressed with the concept,

v is the fluid flow speed through the duct **11**.

Acoustic node defines the change of sign of the pressure with reference to the nominal pressure.

In addition, the distances **D1** and **D2** are measured between the axes of the nozzles **16** of the injectors **12, 13, 14, 15** or, in case an injector comprises more rows of nozzles **16** (all injecting into the same zone being the centre or the wall zone), with reference to an average position between the two or more axes of the nozzles **16** of this injector (see e.g. FIG. 7).

As an example, FIG. 5 shows one wall of the duct **11** and the pressure in relation to an axial coordinate thereof. From this figure it can be acknowledged that the distance of the first injector **12** from the second injector **13** is $D1 = \lambda_{conv}/2 = v/2f_1$ and likewise the distance of the third injector **14** from the fourth injector **15** is $D2 = \lambda_{conv}/2 = v/2f_2$ because in

this example between the first and second injectors **12, 13** and third and fourth injectors **14, 15** no acoustic nodes are present.

FIG. 6 is similar to FIG. 5; from this figure it can be acknowledged that the distance of the first injector **12** from the second injector **13** is $D1 = \lambda_{conv}/2 = v/2f_1$ because there is no acoustic node between them and the distance of the third injector **14** from the fourth injector **15** is $D2 = \lambda_{conv} = v/f_2$ because an acoustic node is provided between them (the acoustic node being identified by reference 22).

Advantageously, f_1 is greater than f_2 . Both f_1 and f_2 are low frequencies e.g. below 150 Hz.

The operation of the mixer and gas turbine having such a mixer is apparent from that described and illustrated and is substantially the following.

Air is compressed at the compressor **2** and is supplied into the burner **3a** where fuel is supplied and mixed with the compressed air, generating a mixture that combusts in the combustor **3b** with a flame **20a**; the hot gas generated through this combustion passes through the transition piece **3c** and enters the mixer **4** (in particular the duct **11** of the mixer **4**).

At the mixer **4** air is injected into the hot gas via the first, second, third, fourth injectors **12, 13, 14, 15** and via possible additional injectors.

This configuration allows a selective cancellation of the mass flow oscillations, because different zones of the cross section of the duct **11** are responsible for generating pulsations of different frequency. In particular, as indicated above, the zones closer to the duct wall have a higher frequency while the zones farther from the duct walls (i.e. at the centre of the duct) have a lower frequency.

FIG. 8 shows an example of a mixer having a plurality of injectors (more than four).

Naturally the features described may be independently provided from one another. For example, the features of each of the attached claims can be applied independently of the features of the other claims.

In practice the materials used and the dimensions as well as the injector shapes can be chosen at will according to requirements and to the state of the art.

The invention claimed is:

1. A method of dampening oscillating frequencies in a gas turbine mixer, the gas turbine mixer comprising a housing, a duct within the housing, a first injector and a second injector, each arranged to inject a fluid at a center zone of the duct, a third injector and a fourth injector, each arranged to inject the fluid at a wall zone of the duct, the method comprising:

either: (a) injecting the fluid through the first injector at a distance $D1=v/2f_1$, or odd integer multiples of $D1$, from the second injector in the absence of an acoustic node between the second injector and the first injector, or (b) injecting the fluid through the first injector at a distance $D1=v/f_1$, or full wave length integer multiples of $D1$, in the presence of an acoustic node between the second injector and the first injector,

and either: (c) injecting the fluid through the third injector at a distance $D2=v/2f_2$, or odd integer multiples of $D2$ from the fourth injector in the absence of an acoustic node between the third injector and the fourth injector, or (d) injecting the fluid through the third injector at a distance $D2=v/f_2$ from the fourth injector in the presence of an acoustic node between the third injector and the fourth injector,

wherein f_1 is an oscillating frequency to be damped at the wall zone of the duct,

f_2 is an oscillating frequency to be damped at the center zone of the duct,

v is a fluid flow speed through the duct, and

f_1 is greater than f_2 .

2. The method of claim 1, wherein both f_1 and f_2 are lower than 150 Hz.

3. The method of claim 1, wherein the first injector and/or the second injector and/or the third injector and/or the fourth injector comprise a plurality of rows of nozzles close to one another.

4. The method of claim 3, wherein nozzles of different rows of nozzles of the first injector, the second injector, the third injector, or the fourth injector have different penetration.

5. The method of claim 3, wherein nozzles of a same row of nozzles have different penetration.

6. A method of operating a gas turbine, wherein the gas turbine comprises a compressor, a first combustion chamber, a second combustion chamber fed with combustion gases coming from the first combustion chamber, a turbine and a mixer between the first combustion chamber and the second combustion chamber, wherein the mixer comprises a housing, a duct within the housing, a first injector and a second injector, each arranged to inject a fluid at a center zone of the duct, a third injector and a fourth injector, each arranged to inject the fluid at a wall zone of the duct, the method comprising:

either: (a) injecting the fluid through the first injector at a distance $D1=v/2f_1$, or odd integer multiples of $D1$ from the second injector in the absence of an acoustic node between the second injector and the first injector, or (b) injecting the fluid through the first injector at a distance $D1=v/f_1$, or full wave length integer multiples of $D1$ in the presence of an acoustic node between the second injector and the first injector,

5

and either: (c) injecting the fluid through the third injector at a distance $D2=v/2f_2$, or odd integer multiples of $D2$, from the fourth injector in the absence of an acoustic node between the third injector and the fourth injector, or (d) injecting the fluid through the third injector at a distance $D2=v/f_2$ from the fourth injector in the presence of an acoustic node between the third injector and the fourth injector,

wherein f_1 is an oscillating frequency to be damped at the wall zone of the duct,

f_2 is an oscillating frequency to be damped at the center zone of the duct,

v is a fluid flow speed through the duct, and

f_1 is greater than f_2 .

10 7. The method of claim 6, wherein both f_1 and f_2 are lower than 150 Hz.

8. The method of claim 6, wherein at least one of the first injector, the second injector, the third injector or the fourth injector comprises a plurality of rows of nozzles close to one another.

15 9. The method of claim 8, wherein nozzles of different rows of nozzles of the first injector, the second injector, the third injector, or the fourth injector have different penetration.

10. The method of claim 8, wherein nozzles of a same row of nozzles have different penetration.

11. A method of operating a gas turbine, comprising:

combusting a fuel in a first combustion chamber, thereby

producing a hot gas;

flowing the hot gas through a mixer; and

either: (a) injecting a fluid in the mixer at a first injection location at a distance $D1=v/2f_1$, or odd integer multiples of $D1$, from a second injection location if there are no acoustic nodes between the second injection location and the first injection location, or (b) injecting the fluid at the first injection location at a distance $D1=v/f_1$, or full wave length integer multiples of $D1$, if there is at least one acoustic node between the second injection location and the first injection location,

and either: (c) injecting the fluid at a third injection location at a distance $D2=v/2f_2$ or odd integer multiples of $D2$, from a fourth injection location if there are no acoustic nodes between the third injection location and the fourth injection location, or (d) injecting the fluid at the third injection location at a distance $D2=v/f_2$ from the fourth injection location if there is at least one acoustic node between the third injection location and the fourth injection location,

wherein f_1 is an oscillating frequency to be damped at a wall zone of a duct of the mixer,

f_2 is an oscillating frequency to be damped at a center zone of the duct,

v is a fluid flow speed through the duct, and

f_1 is greater than f_2 .

15 12. The method of claim 11, wherein injecting the fluid in the mixer at the first injection location includes injecting the fluid at the center zone of the duct.

13. The method of claim 11, wherein injecting the fluid at the third injection location includes injecting the fluid at the wall zone of the duct.

14. The method of claim 11, comprising directing a mixture of the hot gas and the injected fluid to a second combustion chamber of the gas turbine.

15. The method of claim 11, wherein both f_1 and f_2 are lower than 150 Hz.

16. The method of claim 11, wherein the mixer comprises at least a first injector, a second injector, a third injector and

a fourth injector and wherein at least one of the first injector, the second injector, the third injector or the fourth injector comprises a plurality of rows of nozzles close to one another.

17. The method of claim 16, wherein nozzles of different rows of nozzles of the first injector, the second injector, the third injector, or the fourth injector have different penetration. 5

18. The method of claim 16, wherein nozzles of a same row of nozzles have different penetration.
